[57] **CLAIM**

The ornamental design for a pivotally mounted motorcycle hand lever, as shown and described.

DESCRIPTION

FIG. 1 is a left front perspective of a pivotally mounted motorcycle hand lever, showing my new design;

FIG. 2 is a top plan view, thereof;

FIG. 3 is a front elevational view, thereof;

FIG. 4 is an end elevational view thereof;

FIG. 5 is a rear elevational view, thereof;

FIG. 6 is a bottom plan view, thereof;

FIG. 7 is an end elevational view thereof opposite to that shown in FIG. 4; and

FIG. 8 is an end elevational view thereof similar to that shown in FIG. 7 but with the hand lever rotated in an alternate position.
